UNITED STATES PATENT OFFICE.

HERBERT E. WHITE, OF YOUNGSTOWN, OHIO, ASSIGNOR TO TRUSCON STEEL COMPANY, OF YOUNGSTOWN, OHIO, A CORPORATION OF MICHIGAN.

SAND-RETAINING BAR OR PLATE FOR FOUNDRY FLASKS.

Application filed May 23, 1922. Serial No. 562,979.

To all whom it may concern:

Be it known that I, HERBERT E. WHITE, citizen of the United States, residing at Youngstown, county of Mahoning and State 5 of Ohio, have invented certain new and useful Improvements in Sand-Retaining Bars or Plates for Foundry Flasks, of which the following is a specification.

This invention relates to an improved 10 form or construction of sand retaining and reinforcing bar or plate for use in connection with foundry molding flasks.

The object of the invention is to provide an improved bar or plate adapted to be 15 readily produced at low cost and having parts thereof expanded or pressed out of the plane of the bar or plate in order to form an effective interlock with the sand with which the flask is filled to thereby more effectually retain the sand in place, and also to increase 20 the strength of the bar or plate in order to more effectually reinforce or stiffen the flask.

The invention is illustrated in the accompanying drawings, in which

25 Figure 1 is a plan view of the cope member of a foundry flask having two sand retaining and reinforcing bars formed in accordance with the present invention,

Figure 2 is a cross-sectional view of the 30 cope member shown in Figure 1,

Figure 3 is a sectional view of the improved sand retaining bar or plate taken on the line III—III of Figure 2,

Figure 4 is a transverse sectional view of 35 the sand retaining bar or plate taken on the line IV—IV of Figure 2, and

Figure 5 is a similar sectional view of a somewhat modified form of sand retaining bar or plate.

40 The cope member of the foundry flask illustrated in Figures 1 and 2 is of rectangular form having the opposite side walls 2 and the opposite end walls 3, these walls being formed around their upper edges with

45 an outwardly directed flange 4 and around their lower edges with an inwardly directed flange 5. The side and end walls 2 and 3 of the cope member are formed with outwardly pressed sand retaining corrugations 6 and

50 the end walls are provided with apertured lugs 7 to receive the aligning pins of the drag member of the flask. At the four corners of the cope member are arranged handles 8 by which the cope member may be

lifted. The flask member itself does not, of course, form any part of the present invention, the particular construction shown forming the subject matter of Patent No. 1,447,666 to Jencks et al., and being fully described and claimed therein.

It will, of course, be understood that the subject matter of the present invention is not restricted to its use with the specific construction of flask illustrated, but is applicable to substantially all forms of foundry 65 flasks.

The flask member illustrated is shown equipped with two of the improved sand retaining bars in accordance with the present invention, the bars extending between 70 the opposite side walls 2 and being secured to these side walls in any suitable manner, as by welding as indicated in Figure 1. The retaining bar or plate 9 comprises a single strip or sheet of metal which is provided 75 with one or more longitudinal rows or series of transversely extending slits 10 as shown particularly in Figure 2. The metal of the plate between adjacent pairs of slits 10 is expanded or pressed out of the plane 80 of the metal to one or both sides of the plate to form projecting loops 11, as indicated most clearly in Figures 3, 4 and 5.

In the particular form of bar illustrated in the drawings it will be seen from Figure 85 3 that the portion of the bar or plate between the end of the plate and the first slit of the row thereof is left flat and that the metal of the bar or plate between the first pair of slits is pressed downwardly out of 90 the plane of the plate and the metal between the succeeding pairs of slits is pressed alternately upwardly and downwardly out of the plane of the plate in order to provide alternate downwardly and upwardly projecting loops 11 of a form such as that shown in Figure 4.

In the form of bar or plate shown in Figure 4 and at the transverse plane of the line 100 IV—IV the metal between the slits of the central row or series thereof is pressed upwardly while the metal between the aligned slits in the two outer rows or series thereof is pressed downwardly out of the plane of the plate so that the transverse section of 105 the plate at this point is as indicated by the cross-hatched portion of the figure. The metal between the succeeding pair of slits

of the central row or series is pressed downwardly, and the metal between the corresponding slits of the outer row is pressed upwardly out of the plane of the plate as 5 also indicated in Figure 4 by the non-cross-hatched portions of this figure.

In the construction shown in Figure 5, the metal between aligned or corresponding pairs of slits of all of the rows or series 10 thereof is pressed in one direction out of the plane of the plate, while the metal between the succeeding aligned or corresponding pairs of slits of all three rows thereof is pressed in the opposite direction, as clearly 15 shown in the figure.

It will be readily understood that the bar or plate provided in the manner described with the projecting loops 11 will form an effective interlock with the sand which is 20 packed into the flask member and that the sand will be securely retained in place within the flask. The bar or plate forms in effect an open mesh structure through the meshes of which the sand may pass so that 25 the sand surrounds and securely interlocks with all parts of the bar or plate instead of simply frictionally engaging the opposite surfaces of the bar or plate as in the usual forms of such bars.

30 It will be understood that the invention is not restricted to the particular constructions of bar or plate shown in the drawings, as the same may be varied in form and arrangement without departing from the scope of 35 the invention.

What I claim and desire to secure by Letters Patent is:—

1. A sand retaining bar or plate for foundry flasks, comprising a sheet or strip 40 of metal having portions thereof intermediate the longitudinal edges of the sheet expanded or pressed out of the original plane of the sheet to provide apertures through said sheet.

45 2. A sand retaining bar or plate for foundry flasks, comprising a sheet or strip of metal formed intermediate the edges of the sheet with a series of parallel slits, the metal between adjacent slits being pressed 50 out of the plane of the sheet.

55 3. A sand retaining bar or plate for foundry flasks, comprising a sheet or strip of metal formed intermediate the edges of the sheet with a series of parallel slits, the metal between alternate pairs of slits being

pressed in opposite directions out of the plane of the sheet.

4. A sand retaining bar or plate for foundry flasks, comprising a sheet or strip of metal formed intermediate the edges of 60 the sheet with a plurality of series of parallel slits, the metal between alternate pairs of slits of each row thereof being pressed in opposite directions out of the plane of the sheet.

65 5. A sand retaining bar or plate for foundry flasks, comprising a sheet or strip of metal formed intermediate the edges of the sheet with a plurality of series of parallel slits, the metal between alternate pairs of slits of each row being pressed in opposite directions out of the plane of the sheet; and the metal between corresponding pairs of slits of alternate rows being pressed 70 in opposite directions.

75 6. A sand retaining bar or plate for foundry flasks, comprising a sheet or strip of metal having integral loops pressed out to one side of the plane of the sheet.

80 7. A sand retaining bar or plate for foundry flasks, comprising a sheet or strip of metal having integral loops pressed out to opposite sides of the plane of the sheet.

85 8. A sand retaining bar or plate for foundry flasks, comprising a sheet or strip of metal having the portion thereof intermediate the edges thereof slitted and expanded to form open meshes.

90 9. A sand retaining bar or plate for foundry flasks, comprising a strip of metal formed intermediate the edges thereof with a longitudinally extending series of parallel slits, the metal between adjacent slits being forced outwardly out of the plane of the strip to form open meshes.

95 10. A sand retaining bar or plate for foundry flasks, comprising a sheet or strip of metal formed intermediate the edges thereof with a plurality of series of parallel slits, the metal between the various pairs 100 of slits being expanded alternately to opposite sides of the original plane of the sheet in order to form an open mesh-work.

In testimony whereof I affix my signature in presence of two witnesses,

HERBERT E. WHITE.
